UNITED STATES PATENT OFFICE.

BENAJAH WILCOX, OF WOODHULL, NEW YORK.

WAGON-BRAKE.

SPECIFICATION forming part of Letters Patent No. 399,958, dated March 19, 1889.

Application filed December 11, 1888. Serial No. 293,295. (No model.)

To all whom it may concern:

Be it known that I, BENAJAH WILCOX, a citizen of the United States, residing at Woodhull, in the county of Steuben and State of New York, have invented a new and useful Improvement in Automatic Wagon-Brakes, of which the following is a specification.

My invention relates to improvements in automatic wagon-brakes; and it consists in 10 certain novel features, hereinafter described and claimed.

In the accompanying drawings, Figure 1 is a side view of a wagon provided with my brake, with one of the front wheels removed. 15 Fig. 2 is a similar view showing the brake applied to the wheels. Fig. 3 is a detail perspective view of the tongue and the cross-bar and the bands supporting the rear end of the same. 20 Referring to the drawings by letter, A designates the body of the wagon, of the usual or any preferred construction. The rear wheels, B, are mounted on an axle, C, which is secured to the wagon-body through the medium of the 25 springs D, as shown.

E designates the king-bolt, which is mounted in the front end of the body and has a cross-head, F, secured to its lower end.

G designates a spring which has its arms 30 H H secured to the cross-head near its opposite ends and extended forward beyond the wagon-body and thence backward, forming a U-shaped portion, I, to which the front axle, J, is secured, the front wheels, K, being mounted on the said axle.

To the front ends of the spring G, I secure the cross-bar L, having a horizontal slot, M, at its center, as shown. To the ends of the said cross-bar L, I secure the brace-rods N, which 40 converge forward therefrom and have their front ends connected by the bands O O, as shown. The tongue P has its rear end mounted in these bands and is adapted to move longitudinally through the same. A metallic strap, 45 Q, is secured to the rear end of the tongue and projects rearward through the slot M in the cross-bar L, as shown.

R designates the rock-shaft, which is mounted on the under side of the wagon-body in advance of the rear wheels and has its ends bent 50 downward, forming crank-arms S, to the ends of which the brake-shoes T are secured. The

rock-shaft is further provided at its center with the depending crank-arm V, and the said crank-arm is connected to the strap Q by a 55 connecting-rod, W, as shown. The front end of this connecting-rod is pivoted to the rear end of the said strap Q, and its rear end is provided with a series of transverse openings, X, through any one of which and a similar opening in the end of the crank-arm V a pivot-pin, Y, is inserted.

From the foregoing description it will be seen that when draft is applied to the tongue it will be drawn forward and the brake-shoes 65 consequently held out of contact with the rear wheels, as clearly shown in Fig. 1. When going downhill, the team will hold back on the tongue, and the same will consequently be forced backward through the bands 70 and the cross-bar, thereby pushing the connecting-bar rearwardly and applying the brake-shoes to the wheels, as will be readily understood on reference to Fig. 3, consequently retarding the motion of the vehicle. 75

When it is desired to back the wagon on a level road, the tongue is prevented from moving longitudinally by means of a spring-catch, a, mounted on the upper side of the tongue. This catch consists of a lever fulcrumed at its 80 center upon a headed stud or pin, b, on the upper side of the tongue. A spring, c, is arranged around this stud or pin and bears on the upper side of the lever, and is thereby adapted to hold the lever in either of its adjusted positions. By depressing the rear end of this lever it will be made to contact with the band O, so as to prevent movement of the tongue, and by depressing its front end the rear end will be raised so as to clear the band. 90

From the foregoing description, taken in connection with the accompanying drawings, it will be seen that I have provided an extremely simple and efficient brace, by the use of which the speed of the wagon will be automatically controlled. The tongue is held firmly in its position and prevented from vibrating; but it is at the same time allowed the necessary endwise movement to secure the proper operation of the device. The connecting-rod, 95 it will be observed, is provided with a series of transverse openings in its rear end, so that the brakes can be manufactured and sold separately from the wagon and can be readily 100

applied and adjusted to the length of the wagon-body. These openings, furthermore, enable the user of my brake to adjust it so as to apply more or less pressure to the wheels, 5 as will be readily understood.

Having thus described my invention, what I claim, and desire to secure by Letters Patent, is—

1. In an automatic wagon-brake, the combination, with the wagon-body and front axle, 10 of the spring secured to and projected forward from the same, the cross-bar secured to the front ends of said spring, the bands supported by said cross-bar, the tongue supported 15 by the said bands and cross-bar and adapted to move longitudinally, the rock-shaft journaled on the under side of the wagon-body and carrying the brake-shoes, and connections between the said tongue and said rock-shaft, 20 as set forth.

2. The combination of the wagon-body, the springs projecting forward from the front end 25 of the same, the cross-bar secured to said springs, having the central horizontal slot, the

braces secured to the ends of said cross-bar 25 and converging therefrom, the bands connecting the front ends of said braces, the tongue having its rear end mounted in said bands, the strap secured to the tongue and projecting through the slot in the cross-bar, the rock- 30 shaft journaled on the under side of the wagon-body and carrying the brake-shoes and having a depending central crank-arm, and the connecting-rod having its front end pivoted to the strap secured to the rear end of 35 the tongue and its rear end pivoted to the central crank-arm of the rock-shaft, as specified.

3. The combination of the band, the tongue, the headed stud, the lever fulcrumed on said stud, and the spring coiled around said stud 40 and bearing on the lever, as set forth.

In testimony that I claim the foregoing as my own I have hereto affixed my signature in presence of two witnesses.

BENAJAH WILCOX.
